(57) **CLAIM**

The ornamental design for a briefcase, as shown and described.

DESCRIPTION

FIG. 1 is a perspective view of a briefcase showing my new design according to a first embodiment;

FIG. 2 is a perspective view of a briefcase showing my new design according to a second embodiment;

FIG. 3 is a front elevational view of the briefcase according to the embodiment of FIG. 1;

FIG. 4 is a front elevational view of the briefcase according to the embodiment of FIG. 2;

FIG. 5 is a rear elevational view of the briefcase according to the embodiment of FIG. 1;

FIG. 6 is a rear elevational view of the briefcase according to the embodiment of FIG. 2;

FIG. 7 is a side elevational view of the briefcase according to the embodiment of FIG. 2, the opposite side being a mirror image thereof;

FIG. 8 is a top view of the briefcase according to the embodiment of FIG. 1;

FIG. 9 is a bottom view of the briefcase according to the embodiment of FIG. 1; and,

FIG. 10 is a view of the briefcase according to the embodiment of FIG. 1 in the opened position.

The broken lines illustrate portions of the briefcase, according to the first and second embodiments, which form no part of the claimed design.
